CLAIM

The ornamental design for a housing for a local area network unit, as shown and described.

DESCRIPTION

FIG. 1 is a top, front, left side perspective view of a housing for a local area network unit showing our new design in the closed position;

FIG. 2 is a front elevational view thereof on an enlarged scale;

FIG. 3 is a rear elevational view thereof on an enlarged scale;

FIG. 4 is a right side elevational view thereof on an enlarged scale;

FIG. 5 is a left side elevational view thereof on an enlarged scale;

FIG. 6 is a top plan view thereof on an enlarged scale;

FIG. 7 is a bottom plan view thereof on an enlarged scale.

FIG. 2

FIG. 3

*FIG. 4**FIG. 5**FIG. 6*

FIG. 7
